[57] CLAIM

The ornamental design of a golf club, substantially as shown.

DESCRIPTION

FIG. 1 is a front perspective view of the golf club showing my new design;

FIG. 2 is a rear perspective view of the golf club shown in FIG. 1;

FIG. 3 is a fragmentary, enlarged front elevation view of the head and portion of the shaft of the golf club shown in FIGS. 1 and 2;

FIG. 4 is a fragmentary, enlarged end elevation view of the head and portion of the shaft of the golf club shown in FIGS. 1 and 2;

FIG. 5 is a fragmentary, enlarged rear elevation view of the head and portion of the shaft of the golf club shown in FIGS. 1 and 2.
